END STAND OR SIMILAR ARTICLE

Hugo A. Johnson, Brooklyn, N. Y.

Application April 1, 1952, Serial No. 19,142

Term of patent 14 years

(Cl. D33—3)

To all whom it may concern:

Be it known that I, Hugo A. Johnson, a citizen of the United States, residing at Brooklyn, in the county of Kings and State of New York, have invented a new, original, and ornamental Design for an End Stand or Similar Article, of which the following is a specification, reference being had to the accompanying drawing, forming part thereof.

In the drawing:

Fig. 1 is a front elevational view of an end stand or similar article, showing my new design;

Fig. 2 is a rear elevational view of the same;

Fig. 3 is a top plan view thereof.

I claim:

The ornamental design for an end stand or similar article, as shown.

HUGO A. JOHNSON.
